UNITED STATES PATENT OFFICE.

JULIA LITWIN, OF BUFFALO, NEW YORK.

DESIGN FOR A FISH LIFTER.

Application filed June 14, 1928. Serial No. 27,118. Term of patent 14 years.

To all whom it may concern:

Be it known that I, JULIA LITWIN, a citizen of the United States, residing at Buffalo, in the county of Erie and State of New York, have invented a new, original, and ornamental Design for a Fish Lifter, of which the following is a specification, reference being had to the accompanying drawing, forming a part thereof.

In the accompanying drawings:—
Figure 1 is a face view of the fish lifter.
Figure 2 is an edge view thereof.

I claim:
The ornamental design for a fish lifter, substantially as shown.

JULIA LITWIN.
